UNITED STATES PATENT OFFICE

JOHN W. FITZ GERALD, OF MILWAUKEE, WISCONSIN, ASSIGNOR TO BRIGGS AND STRATTON CORPORATION, OF MILWAUKEE, WISCONSIN, A CORPORATION OF DELAWARE

PADLOCK

Application filed December 19, 1928. Serial No. 326,913.

This invention relates to certain new and useful improvements in padlocks and has as an object the provision of an improved structure whereby the manufacturing processes are materially simplified to effect a saving in both labor and material.

A further object of this invention resides in the provision of an improved padlock structure which is so designed and constructed that the parts thereof may be finished prior to assembling to thus effect economy and permit the obtaining of a better appearing and more durable finish.

And a more specific object of this invention resides in the provision of an improved padlock construction wherein a common means mounts a name plate and secures the parts in assembled position.

With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawing, I have illustrated one complete example of the physical embodiment of my invention constructed according to the best mode I have so far devised for the practical application of the principles thereof, and in which:

Figure 1 is a view, partly in section and partly in elevation, of a padlock embodying my invention, said view being taken on the plane of the line 1—1 of Figure 3;

Figure 2 is an elevational view of a padlock with parts broken away and in section to illustrate structural details;

Figure 3 is a view looking down on the top of the padlock with the cover removed and the shackle in section, said view being taken through Figure 1 on the plane of the line 3—3, and

Figure 4 is a perspective view of a padlock with the parts disassembled.

Referring now more particularly to the accompanying drawing, in which like num-

erals designate like parts throughout the several views, 10 represents a shell or retainer formed by die-casting or any other means and which is of the desired shape and size depending upon the use to which the padlock is to be applied. The shell or retainer has a central bore 11 in which a lock cylinder 12 is rotatably mounted and held against movement outwardly of the bottom or lower end 13 thereof by a shoulder 14 formed by reducing the diameter of the bore 11 and cooperating with a shoulder 15 formed by reducing the outer end portion of the cylinder.

The retainer 10 is further provided with two parallel bores 16 and 17 disposed on diametrically opposite sides of bore 11 and terminating short of the bottom of the retainer so that access may be had thereto only from the top, the bores 16 and 17 receiving the shanks 18 and 19, respectively, of a padlock shackle 20. The shank 18 is longer than the shank 19 which is provided with opposed locking recesses or notches 21 which cooperate with a hair-pin shaped locking member 22, to be later described.

The top face of the retainer 10 is recessed to receive the hair-spring locking member 22 which is formed of strip spring metal having its free ends 23 yieldably urged together and extended over the bore 17 of the retainer to receive the shank 19 therebetween. When the shackle is in locked position, the notches or recesses 21 register with the ends 23 of the hair-pin locking member so that the outward movement of the shank is restrained. The other shank 18 of the shackle forms a pivot member and is permitted axial movement in its bore 16 to free the shorter shank 17 from the retainer and permit the pivoting of the shackle, but is held against detachment from the retainer in a manner now about to be described.

The hair-pin locking member is held in position by lugs 22' extended into the retainer top recess and disposed between the arms of the member, the closed end 24 of which overlies the bore 16 to engage in a slot or cut away portion 25 in the inner side of the shank 18 and cooperates with the

shoulder 26 of an enlargement 27 on the extreme inner end of the shank 18 to prevent the outward movement of the shank beyond the member 22, as will be evident. For a short distance above the enlargement 27, the shank 18 is turned, as at 28, to permit the swiveling of the shank 18 when in its full outward position. The shank 18 is bored to receive an expansile spring 29 which normally urges the shackle outwardly when its shank 19 is freed by manipulation of the cylinder 12.

The cylinder 12 has a cam 30 on its upper end which is normally disposed between the sides of the member 22 and when in its locked position the cam is disposed lengthwise of the member 22 in the manner illustrated in Figure 3. Rotation of the cylinder by a proper key 31 spreads the ends 23 of the hair-pin locking member to free them of the notches or locking recesses 21 and permit the outwardly opening of the padlock.

The top of the retainer and the locking member are protected by a cover 32 of a shape to conform with the shape of the retainer 10 but of smaller size and having a marginal depending flange 33 engageable in a correspondingly shaped groove or channel 34 in the top of the retainer, in the manner best shown in Figures 1 and 2, the cover having apertures 34' and 35 through which the shackle shanks 18 and 19, respectively, pass.

The cover member is provided with a pair of spaced depending tongues or lugs 36 at each long side thereof which pass into correspondingly shaped openings or recesses 37 in the retainer, the tongues having apertures 38 which register with apertures 39 communicating with one side face of the retainer 10 but terminating in the recesses 37 near the opposite side thereof.

In assembling the lock, the cylinder 12 is positioned in its bore 11, cover 32 is engaged over the shanks of the shackle 20 and the shackle shank 18 inserted partly in the bore 16 and the hair-pin locking member 22 then positioned in place. The cover is then engaged over the retainer with its flange 33 pressed in the groove or channel 34. A name plate 40 is then placed on the face of the retainer with which the apertures 39 communicate, which is preferably recessed, as at 41, to conform with the shape of the name plate and rivets or other fastening means 42 are pressed through the apertures in the plate 40 and the apertures 39 passing through the apertures 38 on the tongues 36 securing the cover in place. The rivets 42 are such that when pressed in position they are held against retraction and thus the entire lock is held in assembled position.

By simultaneously securing the name plate 40 and the cover 32 against detachment, the primary object of the rivets 42 is concealed,

as their function appears to be only that of mounting the name plate.

From the foregoing description, taken in connection with the accompanying drawing, it will be readily apparent to those skilled in the art to which an invention of the character described appertains, that I provide a novel and improved padlock construction which is extremely simple, permitting the finishing of the parts prior to assembly, and which readily lends itself to manufacture in all sizes to afford ample protection at all times.

What I claim as my invention is:

1. A padlock, comprising a retainer having three parallel bores therein arranged with their axes in approximately transverse alignment, the central bore extending through the retainer, a key controlled lock cylinder mounted in the central bore adapted to be inserted therein from the top of the retainer, means preventing axial alignment of the lock cylinder in its bore beyond the bottom face of said retainer, an approximately U-shaped shackle member having its shanks engageable in the other bores of the retainer, a locking member disposed in the top face of the retainer, means carried by said locking member and engageable with one shank of the shackle to prevent movement of the shackle in the retainer, means whereby rotation of the cylinder disengages the locking member from said shackle shank to permit its movement from the retainer, and means whereby said locking member likewise prevents detachment of the shackle from the retainer.

2. A padlock, comprising a retainer having parallel bores therein communicating with its top, one bore extending through the retainer to its bottom, a key controlled lock cylinder mounted in the bore extended through the retainer and adapted to be inserted therein from the top, means preventing axial movement of the lock cylinder in its bore beyond the bottom of the retainer, a shackle member having a shank engageable in the other bore of the retainer, a locking member disposed in a recess in the top face of the retainer and engageable with the shackle shank to lock the same in the retainer, means whereby rotation of the cylinder disengages the locking member from the shackle shank, a cover adapted to be engaged over the top of the retainer, tongues projected from the marginal edge portion of the cover into recesses in the retainer to intersect transverse apertures extended into the retainer from one side face to a point short of the other, and fastening means adapted to be secured in said transverse openings to pass through said tongues and secure the cover to the retainer.

3. A padlock, comprising a retainer, a substantially U shaped shackle adapted to

- be secured in the retainer, a locking member carried by the retainer and engageable with one of the shanks of the shackle to restrict movement thereof with respect to the retainer, means for releasing said locking member to permit movement of said shank away from the retainer, and means whereby said locking member cooperates with the other shank of the shackle to prevent detachment of the shackle from the retainer.
4. A padlock, comprising a retainer, a shackle having parallel members adapted to be received in apertures in the retainer, a locking member engageable with one shackle member to restrict movement thereof with respect to the retainer, means for freeing said shackle member from the locking member, said other shackle member being freely slidable within its aperture in the retainer upon the release of the first mentioned shackle member, and means whereby said locking member cooperates with said other shackle member to restrict outward movement of the shackle with respect to the retainer to prevent its detachment therefrom.
5. A padlock, comprising a retainer, a shackle having parallel members adapted to be received in apertures in said retainer, a locking member engageable with one shackle member to restrict movement thereof with respect to the retainer, means for freeing said shackle member from the locking member, the other shackle member being freely slidable within its aperture in the retainer upon the release of the first mentioned shackle member, means whereby said locking member restricts outward movement of the shackle with respect to the retainer to prevent its detachment therefrom, and means whereby the shackle is freely rotatable about the axis of its second mentioned member after a predetermined outward movement of the shackle.
6. A padlock, comprising a retainer having a plurality of substantially parallel bores, a shackle receivable in two of said bores, a key controlled lock cylinder rotatable in another bore and restricted against outward movement therethrough in one direction, a locking member carried by the retainer and operable to engage the shackle to restrict movement thereof with respect to the retainer, a cover having apertures through which the shackle extends and maintaining the lock cylinder and locking member in their proper assembled position within the retainer, and means remote from the cover for securing the same against detachment from the retainer.
7. A padlock comprising a retainer having spaced parallel bores, a shackle having parallel members receivable in said bores, an abutment carried by each parallel member, said abutments being on different planes, a locking member carried by the retainer and having a portion normally extended into each bore whereby one of said portions engages one of the abutments to secure the shackle in the retainer and the other portion of the locking member engages the other abutment when the shackle is released to prevent detachment thereof from the retainer.
8. A padlock comprising a retainer, a shackle having parallel members adapted to be received in apertures in the retainer, an abutment on one of said parallel members, a locking member carried by the retainer and engageable with said abutment to restrict movement of the shackle with respect to the retainer, means for freeing said abutment from the locking member to release the shackle for outward movement with respect to the retainer, and an abutment on the other parallel member engageable with the locking member upon outward movement of the shackle with respect to the retainer to prevent detachment of the shackle from the retainer.
9. A padlock comprising a retainer, a shackle having parallel members adapted to be received in apertures in the retainer, each parallel member having a portion cut away to provide an abutment, the cut away portion of one parallel member being longer than that of the other, and a locking member having portions normally extended into the cut away portions of the parallel members, the engagement of the locking member with the smaller of the cut away portions serving to restrain the shackle member against longitudinal movement with respect to the retainer and the engagement of the locking member portion with the other cut away portion of the shackle member defining the degree of longitudinal movement of a shackle member with respect to the retainer.
10. A padlock comprising a retainer, a shackle having parallel members adapted to be received in apertures in the retainer, each parallel member having a portion cut away to provide an abutment, a locking member carried by the retainer and having a part fixedly extended into the cut away portion of one parallel member and a part yieldably engageable with the cut away portion of the other parallel member, said last mentioned engagement securing the shackle against movement with respect to the retainer, means for disengaging the locking member from said last mentioned cut away portion to permit movement of the shackle with respect to the retainer, and the engagement of the fixed part of the locking member with the first-mentioned cut away portion defining the movement of the shackle member to prevent detachment thereof from the retainer.
11. A padlock comprising a retainer having spaced parallel bores, a shackle having parallel members adapted to be received in said bores, said parallel members having por-

tions cut away to provide abutments, the cut away portions of one parallel member being longer than the other so that the abutment provided thereby is disposed on a different plane from the other abutment, a substantially U shaped locking member, means mounting the locking member in the retainer with its closed end extended into one of the bores to be engageable with the longer of the two cut away portions and one of its free ends yieldably engaged with the cut away portion of the other parallel member to secure the shackle in closed position, and means for releasing said last mentioned abutment from the locking member to permit movement of the shackle away from the retainer, said movement of the shackle being limited by the engagement of the closed end of the locking member with its cooperating abutment.

20 In testimony whereof I have hereunto affixed my signature.
